UNITED STATES PATENT OFFICE.

JOHN H. GILMAN, OF OTTAWA, ILLINOIS, ASSIGNOR TO KING & HAMILTON COMPANY,
OF OTTAWA, ILLINOIS, A CORPORATION OF ILLINOIS.

GEARING.

1,078,671.

Specification of Letters Patent. Patented Nov. 18, 1913.

Application filed January 25, 1912. Serial No. 673,466.

To all whom it may concern:

Be it known that I, JOHN H. GILMAN, a citizen of the United States, and a resident of Ottawa, in the county of La Salle and 5 State of Illinois, have invented certain new and useful Improvements in Gearing, of which the following is a full, clear, and exact specification.

My invention is concerned with gearing, 10 designed more especially for wagon dumps or hoisting mechanism designed to slowly elevate the front end of a wagon body, thereby tilting it so that its contents can flow through the opened end gate.

15 One feature of my invention is concerned with a novel gearing for said dumps, which gearing is particularly adapted for use where the dump is to be driven by a belt.

Other novel features will be described at 20 length in the specification and particularly pointed out in the claims.

To illustrate my invention, I annex hereunto three sheets of drawings, in which the same reference characters are used to designate 25 identical parts in all the figures, of which,—

Figure 1 is a perspective view of the gearing; Fig. 2 is a side elevation of the framework and the hoisting mechanism; Fig. 3 is 30 a top plan view of the same; Fig. 4 is an end elevation with the gearing mostly removed; Fig. 5 is a plan view in section on the line A—A of Fig. 2; Fig. 6 is a detail in section on the line B—B of Fig. 2; Fig. 7 is a view 35 of the gearing as seen from the back of Fig. 1 and with a portion thereof in section on the vertical plane of the drive shaft; Fig. 8 is a detail showing the means for securing the adjustable bearing shaft; Fig. 9 is a detail 40 in section on the line C—C of Fig. 7; Fig. 10 is a detail on the line D—D of Fig. 7; and Fig. 11 is a detail on the line E—E of Fig. 7.

In carrying out my invention, I may employ 45 the preferred form of framework shown in Figs. 2 to 6, where it will be seen that I employ two end frames made up of the horizontal bottom pieces 20 and 21 and the converging side pieces 22, 23, 24 and 25, the converging 50 side pieces 22 and 24 being secured at their upper ends to the adjacent ends of the cross pieces 26 and 27, while the other ends of said cross pieces are secured to the upper ends of the side pieces 23 and 25. The 55 various members may be bolted and secured

together in any desired manner to form a rigid structure. To prevent the possible spreading of the bases, I connect the bottom pieces 20 and 21 by the pair of tie rods 28 and 29.

60 In the right-hand end of the cross head formed by the cross pieces 26 and 27, I journal the pulley 30, and in the left-hand end I journal the pulleys 31 and 32, and over the pulleys 30 and 31 passes the chain 33, the 65 lower end of which is secured to one end of the lifting frame; while over the pulley 32 passes the chain 34, the lower end of which is secured to the other end of the lifting frame 35, the other ends of the chains 33 and 34 preferably being secured in the yoke 36 carried by the upper end of the rod 37. The lifting frame 35 consists of an open 70 rectangular frame adapted to receive the front wheels of the wagon, so that as it is 75 lifted the front end of the wagon will be raised thereby, and I preferably form the longitudinal members 38 of this lifting frame of a pair of channel bars opening downward, and the transverse or end members are formed by the angle irons 39 shown. The connections for the chains are formed by the converging straps 40 secured at their 80 lower ends to the outer ends of the angle bars 39, while their upper ends are connected to the eyes 41 which embrace the vertical 85 guide bars 42. Additional eyes 43 embracing the guide bars 42 are secured on the vertical flanges of the angle irons 39, and the chains 33 and 34 are connected to bolts connecting the upper ends of the converging straps 40. The guide bars 42 are preferably supported at their upper ends by the angular straps 44, best shown in Fig. 5, the 90 ends of which are bolted to the side bars 22 and 24, and 23 and 25, while the central portions are bolted to the upper ends of the guide bars. The lower ends of the guide bars are likewise supported by similar angular straps 45, which are bolted at their 95 ends to the bottom pieces 20 and 21, and at their central portions to the lower ends of the guide bars 42. With the construction shown and described, it will be apparent 100 that I have produced a rigid metallic frame built up of ordinary structural shapes, and which provides a means for lifting the frame 35 by pulling downward on the rod 37.

105 I secure the gearing, the preferred form 110

of which is shown in Fig. 1, at the bottom of the right-hand frame by bolting thereto the frame casting 46, bolted directly thereto at the lower end, and indirectly at the upper end by means of the offsetting strap 47 provided to take care of the inclination of the side frame. Bolted on this frame casting 46 are a pair of bracket castings 48 and 49, differing somewhat in design, but having the same functions, both of which have at their inner ends bearings for the drive shaft 50, which may be driven by the tumbling rod 51 connected thereto by the universal joint 52, where the dump is to be driven by horsepower. My invention, however, is designed more especially for use in connection with gasoline engines as the motive power, and to this end I secure on the other end of the shaft 50 a spur gear wheel 53 which meshes with a spur pinion 54 preferably formed integral with the driving pulley 55, which, together with the loose pulley 56, are mounted on some suitable adjustable bearing by which the relative sizes of the pinion 54 and the gear wheel 53 may be regulated so that the apparatus can be driven by gasoline engines having different normal speeds. In the preferred form, I employ the bearing rod or shaft 57, which rests in the bearing blocks 58 and 59, which are secured in any necessary position of adjustment on the brackets 48 and 49 by the clips 60 which are passed through the slots 61 and 62 in the bracket castings 48 and 49 and have the nuts 63 screwed on the lower ends to bind the shaft 57 on the blocks 58 and 59, so that the driving pulley 55 and the loose pulley 56 are free to rotate on said shaft.

For the gearing and reversing mechanism which must be employed in these devices, I preferably employ the following: Splined or otherwise secured to slide on but rotate with the shaft 50 is the clutch sleeve 64, provided with the customary annular groove 65 and with the engaging lugs 66 at each end. At one end of the clutch sleeve 64 is the worm 67 mounted to rotate loosely on the shaft 50 and having the engaging lugs 68 adjacent the clutch sleeve. This worm meshes with the worm wheel 69 secured on the shaft 70 journaled in suitable bearings in the framework 46, and having at its inner end the sprocket wheel 71 for a purpose to be described. Loosely journaled on the shaft 50 at the other end of the clutch sleeve is the pinion 72 provided with the clutch lugs 73 and meshing with an idle pinion 74 journaled on the stud 75 carried by the frame casting 46. This idle pinion 74 meshes with a pinion 76 rigidly secured upon the shaft 77 journaled in suitable bearings carried by the frame casting 46. The other end of the shaft 77 has secured thereon the spur gear wheel 78, which

meshes with the spur pinion 79 formed integral with or rigidly secured to the worm 67. With the gearing thus far described, it will be apparent that if the shaft 50 is driven constantly in one direction and the clutch sleeve 64 is shifted to the right in Fig. 1, the shaft 50 will drive the worm 67 through the train of gears 72, 74, 76, 78 and 79 at a certain rate of speed, and it will rotate in the proper direction to lower the frame. If the clutch sleeve 64 is shifted to the left in Fig. 1, the worm 67 will be directly engaged by the clutch and driven directly by the shaft 50 in the opposite direction and at a slower rate of speed, and in the proper direction to lift the frame 35, the train of gearing 78, 76, 74 and 72 now running idly. To control the position of this clutch sleeve 64, I provide the lever pivoted to the frame 46 at 80 and having the vertical arm 81 which may be connected to a horizontal bar or otherwise arranged to be manipulated by hand to throw the clutch sleeve from its neutral disengaged position into its engaged position. The horizontal arm 82 of this lever has the offset portion 83 pivotally connected at 84 to the lower end of the vertical rod 85 which extends upward and preferably passes through a guiding aperture 85^a formed in the cross piece 86 between the bars 22 and 24. This rod has adjustably secured thereon the stop lug 87, the position of which controls the extent to which the frame 35 may be lifted in the operation of the device. The sprocket wheel 71 on the shaft 70 (the rotation of which is effected by the drive shaft and gearing in the manner before described) cooperates with the endless sprocket chain 88 which passes around the sprocket wheel 89 journaled in the yoke 90 which depends from the threaded rod 91, also extending through an aperture 92 in the cross piece 86. A nut 93 on the rod serves to adjust the position of the sprocket wheel 89, and on the side of the chain 88 adjacent to the rod 85, I secure the eye 94 embracing said rod and adapted to contact with the stop 87 at the end of the upward movement of the frame 35 to automatically disengage the clutch, while it engages the end 83 of the arm 82 of the lever to throw it in the other direction and disengage the clutch when the frame 35 reaches the ground. In the other side of the chain 88, I secure the hook 95, in which the lower end of the rod 37 terminates, so that the downward movement of that side of the chain pulls down the rod 37 (preferably guided by passing through an aperture 86^a in the cross piece 86), thereby drawing the chains 33 and 34 over the sheaves and lifting the frame 35. When the movement is reversed, the frame 35 will descend and the rod 37 rise. It will, of course, be understood that the arm 81

is provided with the projection 96 extending into the groove 65.

While I have herein shown and described a novel framework and lifting mechanism 5 with which my gearing herein claimed is adapted to be associated, I do not herein claim said framework and lifting mechanism, but reserve the same for my divisional application No. 698,143, filed May 18, 1912.

10 While I have shown and described my invention in the form which I at present consider best adapted to carry out its purposes, it will be understood that it is capable of modifications, and that I do not desire to be 15 limited in the interpretation of the following claims except as may be necessitated by the state of the prior art.

What I claim as new, and desire to secure by Letters Patent of the United States, is:

20 1. In a device of the class described, the combination with a framework, of a driven shaft associated therewith, gearing for driving said shaft in both directions, a drive shaft for said gearing rotating in one direction, a gear wheel secured to said drive shaft, a pinion meshing with said wheel, a drive pulley secured to rotate with the pinion, and adjustable bearings for said pulley and pinion.

30 2. In a device of the class described, the combination with a framework, of a driven shaft associated therewith, gearing for driving said shaft in both directions, a drive shaft for said gearing rotating in one direction, a gear wheel secured to said drive shaft, a pinion meshing with said wheel, a drive pulley secured to rotate with the pinion, a frame casting attached to the framework, slotted brackets attached to the frame casting, blocks and clips adjustably secured in the slots of the brackets, and a stationary shaft held by the clips upon the blocks and upon which the pulley and pinion are journaled.

45 3. In a device of the class described, the combination with a drive shaft, of a clutch sleeve splined thereon, a clutch pinion loose on said shaft, a combined worm and clutch pinion also loose on said shaft, a countershaft, two pinions secured thereon, one meshing with the combined clutch and worm pinion, an idle pinion interposed between the other of the two pinions and the clutch pinion, a worm wheel meshing with the worm, a shaft on which 50 the worm wheel is secured, a sprocket wheel

on the shaft, a sprocket chain coöperating with the wheel, a shifting lever coöperating with the clutch sleeve, and a stop member on the chain engaging the shifting lever. 60

4. In a device of the class described, the combination with a drive shaft, of a clutch sleeve splined thereon, a clutch pinion loose on said shaft, a combined worm and clutch pinion also loose on said shaft, a countershaft, two pinions secured thereon, one meshing with the combined clutch and worm pinion, an idle pinion interposed between the other of the two pinions and the clutch pinion, a worm wheel meshing with the worm, a shaft on which the worm wheel is secured, a sprocket wheel on the shaft, a sprocket chain coöperating with the wheel, a shifting lever coöperating with the clutch sleeve, a stop member on the chain engaging the shifting lever, and a member connected to said chain and moving therewith. 75

5. In a device of the class described, the combination with a drive shaft, of a clutch sleeve splined thereon, a clutch pinion loose on said shaft, a combined worm and clutch pinion also loose on said shaft, a countershaft, two pinions secured thereon, one meshing with the combined clutch and worm pinion, an idle pinion interposed between the other of the two pinions and the clutch pinion, a worm wheel meshing with the worm, a shaft on which the worm wheel is mounted, and means for shifting the clutch sleeve. 80

6. In a device of the class described, the combination with a drive shaft, of a clutch sleeve splined thereon, a clutch pinion loose on said shaft, a combined worm and clutch pinion also loose on said shaft, a countershaft, two pinions secured thereon, one meshing with the combined clutch and worm pinion, an idle pinion interposed between the other of the two pinions and the clutch pinion, a worm wheel meshing with the worm, a shaft on which the worm wheel is mounted, a shifting lever coöperating with the clutch sleeve, and a stop member actuated to operate the shifting lever by the rotation of the worm-wheel shaft to a certain extent. 100

In witness whereof, I have hereunto set my hand and affixed my seal, this 13th day of January A. D. 1912.

JOHN H. GILMAN. [L. S.]
